UNITED STATES PATENT OFFICE.

ROBERT MATTHEWS, OF MANCHESTER, ENGLAND.

APPARATUS FOR WORKING ORDNANCE.

SPECIFICATION forming part of Letters Patent No. 644,992, dated March 6, 1900.

Application filed August 21, 1899. Serial No. 727,994. (No model.)

To all whom it may concern:

Be it known that I, ROBERT MATTHEWS, engineer, a subject of the Queen of Great Britain, residing at Openshaw, Manchester, in the county of Lancaster, England, have invented certain new and useful Improvements in and Relating to Apparatus for Working Ordnance, of which the following is a specification.

This invention relates to the working of heavy guns, and has for its object to provide means whereby in the event of the failure of the hydraulic or other power employed for running the gun in and out it can be run out at any angle of elevation by hand-operated or other auxiliary gearing and be retained in such position without danger of its running back unintentionally and injuring the gunners or the gearing, such means, however, being so contrived that the gun will not be prevented from recoiling on shock of discharge. For this purpose I employ a slipping pawl or other form of trip-gear which is carried by the cradle or carriage of the gun or some other recoiling part of the mounting, such pawl being adapted to engage with a non-recoiling part of the mounting by the action of a spring which is so loaded as to cause the pawl to retain the gun in its run-out position until it is fired, when the spring will be overcome and permit the pawl to disengage itself and allow the gun to recoil in the ordinary manner.

In order that my said invention may be clearly understood and readily carried into effect, I will proceed to describe the same more fully with reference to the accompanying drawings, in which—

Figure 1 is a sectional side elevation showing one form of my trip-gear apparatus and so much of the gun-mounting as will suffice for a proper explanation of my invention. Fig. 2 is a sectional plan of the apparatus illustrated in Fig. 1. Fig. 3 is a vertical transverse section illustrating the hand-gearing shown in Fig. 1. Fig. 4 is a fragmentary sectional view taken approximately on the line 1 1 of Fig. 1 looking toward the right. Fig. 5 is an enlarged detail view of the slipping pawl slightly varied in construction from that shown in the preceding figures. Fig. 6 is a vertical section of a portion of the gun-

mounting, showing a modification of my apparatus. Fig. 6^a is a fragmentary section, on a larger scale, of a portion of the modified apparatus. Fig. 7 is a vertical section taken approximately on the line 2 2 of Fig. 6 looking toward the right, but showing only the left-hand half of the said figure. Fig. 8 is a detail sectional view taken approximately on the line 3 3 of Fig. 6.

In all the figures like letters of reference indicate similar parts, and in both of the arrangements illustrated the cradle is supposed to have been run forward and to have carried the gun into its firing position.

A is the recoiling part or cradle, in which the gun is mounted in the well-known manner. B is the frame upon which the said cradle slides. C is the piston which works in the hydraulic cylinders D and to which the said cradle is rigidly connected by the socket or bracket E.

Referring more particularly to the arrangement illustrated in Figs. 1 to 5, F is an endless sprocket-chain passing around sprocket-wheels F' F², mounted on stationary axes F³, carried by the under frame of the gun-mounting. One of the sprocket-wheels—viz., F²—is mounted on a sleeve F⁴, that carries a bevel-wheel F⁵, which is capable of being revolved by any suitable hand-operated or other auxiliary gearing provided for the purpose. G is the slipping pawl, which is pivotally mounted at g in the socket or bracket E, with which the cradle is provided, and through such socket the endless chain F passes. g' is the spring by which the said pawl is pressed inwardly to engage with one or other of several projections f f with which the endless chain is provided, these projections being so arranged that when the gun and cradle recoil the nose g² of the said pawl will lie immediately in front of one of the projections, as represented by dotted lines in Fig. 2. Therefore in the event of the failure of the motive power (which in the present instance is hydraulic) for running the gun out to its firing position the said sprocket-chain can be caused to travel in the direction of the arrows, Fig. 2, by operating the aforesaid sprocket-wheels through the auxiliary gearing. Thus the said pawl, and consequently the cradle carrying it, is run forward and the gun is brought to

its firing position, any liability of the pawl's becoming disengaged from the projection during this operation being prevented by the resistance of the said spring g' . The gun having thus been run out, it is maintained in such position by the pawl's engagement with the said projection in the sprocket-chain, and any tendency of the chain or the auxiliary gearing to move backwardly under the weight 10 or the recoil of the gun is avoided by a spring-controlled ratchet H , engaging with ratchet-teeth H' , formed in the face of the bevel-wheel F^5 . In place of this ratchet device I may, however, employ any other appropriate means 15 for the purpose. The nose of the pawl G and the face of the projections with which it engages are inclined, so that on firing the gun the rearward stress on the cradle due to the shock of discharge will cause the pawl to move outwardly against the resistance of the spring g' , whereby the pawl will be disengaged and permit the gun and the cradle to recoil in the usual manner. The said pawl then occupies a position corresponding with 20 that represented by the dotted lines in Fig. 2 ready to be carried forward again by the adjacent projection on the sprocket-chain when the auxiliary gearing is next actuated. When the gun is run out by the ordinary 25 hydraulic or other power provided for the purpose, it will be readily understood that the sprocket-chain remains stationary, and that the pawl G merely runs over the forward projection f as the cradle and its socket E advance, and that on firing the gun the pawl becomes disengaged from this projection by the shock of discharge, as already explained. If desired, the aforesaid projections on the 30 sprocket-chain may be arranged in pairs and the nose of the spring-pawl G formed in the manner illustrated in Fig. 5, so that when the hydraulic or other power apparatus is disabled the said pawl will act to prevent the gun from shifting longitudinally by the rolling 35 of the ship, whether the said gun be run out or run in. The spring g' controlling the pawl is preferably made capable of adjustment, so that its resistance can be increased or diminished to cause the pawl to engage 40 more or less firmly with the projections on the sprocket-chain. I have for this purpose (as best seen in Fig. 5) represented the outer end of the said spring supported by an adjustable screw g^3 , carried by the socket E . By turning this screw in one or other direction 45 the resistance of the spring can be readily varied.

In some cases I construct the aforesaid pawl G with a tail g^4 , Fig. 5, with which a screw 50 g^5 , carried by the socket E , engages. The turning of this screw in the proper direction will cause the said pawl to be set into such a position that its nose will lie out of reach of the aforesaid projections f , whereby said pawl 55 will be thrown entirely out of action.

By arranging the sprocket-chain to pass through the aforesaid socket E , I provide for

effectually supporting the said chain against inward movement, which would otherwise take place by the pressure of the nose of the pawl and render the working of the apparatus unsatisfactory.

The auxiliary gearing illustrated in the drawings for enabling the sprocket-chain to be operated comprises a bevel-pinion F^6 , 75 mounted on a transverse shaft F^7 and formed in one piece, with a bevel-wheel F^8 , that gears with a bevel-pinion F^9 , mounted on an inclined shaft F^{10} , which latter, by bevel-pinions F^{11} F^{12} , is geared with the shaft F^X . By reason 80 of the shaft F being carried by a part of the mounting which receives movement when the gun is elevated or depressed and of the shaft F^X being carried by a part of the mounting which does not so move it is necessary to provide means whereby the relative position of these two shafts can vary in accordance with the alterations in the angle of elevation of the gun. For this purpose the said shaft F^{10} is mounted at its lower end in a socket F^{13} , 90 which is capable of rocking about the axis of the shaft F^7 , and the bevel-pinion F^{11} is adapted to revolve in a bracket F^{14} , which is free to oscillate about the axis of the shaft F^X . The said shaft F^{10} is free to slide through the 95 pinion F^{11} and the bracket F^{14} and is made rectangular to correspond with the hole in the pinion through which it passes, so that while it is free to slide longitudinally, as required, it will always remain in rotative connection 100 with the pinion. If worm and worm-wheel gearing be employed for actuating the said sprocket-chain, the aforesaid ratchet arrangement H H' will be unnecessary.

It will be obvious that instead of arranging 105 the sprocket-chain F to work in a horizontal plane, as represented in the drawings, it can be arranged to work equally well in a vertical plane.

Referring now to the arrangement illustrated by Figs. 6, 6^a, 7, and 8, I have dispensed with the sprocket-chain F and sprocket-wheels F' F^2 illustrated in the previous figures and substituted therefor a rack I , with which gears a toothed pinion I' , carried by a transverse 110 shaft F^7 . This toothed pinion receives its motion from auxiliary gearing, which (with the exception that the socket F^{13} and the bracket F^{14} are inverted) is similar to the auxiliary gearing already referred to in the preceding figures, and therefore needs no further description. The rack I is carried by a downward extension a on the cradle of the gun, but does not recoil with the said cradle. By operating the aforesaid auxiliary gearing 115 120 125 the pinion I' , that gears with the rack, can be revolved in either direction to cause the rack to travel forward or backward, as may be necessary, in the event of the ordinary hydraulic or other power failing. The pawl G , which is also of similar construction to that already described, is adapted to engage with a recess 130 formed by the projections f on the said rack in an analogous manner to that above stated.

with reference to the sprocket-chain F. When the gun is in its firing position, the said pawl will resist the tendency of the gun to run backward under the action of gravity, but, 5 as in the previous arrangement, will give way on shock of discharge and allow the gun to recoil in the ordinary manner, the rack remaining stationary during the recoil by reason of the pinion I' and the other parts of the 10 auxiliary gearing being held by the ratchet H³, Fig. 6, engaging with the ratchet-wheel H², fixed to the shaft F', Fig. 7. H⁴ is a rod which is connected with the ratchet H³ and is under the control of the gunner, so that he 15 can disengage the ratchet from the ratchet-wheel after firing the gun and permit the rack to be moved rearward by the auxiliary gearing for the purpose of bringing the projections f into reengagement with the pawl G. 20 when the latter and the cradle carrying it are in their recoiled position. Then by revolving the auxiliary gearing in the reverse direction, the pawl G being still in engagement with the projections f, the cradle and gun can 25 be run out to their firing position again. In other respects the working of this modified apparatus is similar to that already described. If the aforesaid pawl G be provided with the tailpiece g⁴, the said screw g⁵ will act to prevent 30 the pawl from being pressed inwardly too far by its spring when it becomes disengaged from the rack. The aforesaid ratchet and ratchet-wheel also operate to prevent the gun from running backward while it is 35 being moved to its firing position by the auxiliary gearing. If, however, worm-gearing be employed, the aforesaid ratchet and ratchet-wheel will be unnecessary. Instead of employing only a single pawl G, I may 40 in the present arrangement use a pair of pawls and two racks, as shown, in which case I provide a transverse lever G', centrally pivoted to the cradle at G², the ends of such lever being formed to receive the springs 45 g', by which the pawls are controlled. This lever enables the pressure of the springs on the said pawls to be equalized. The arrangement of the aforesaid pawl on a recoiling part of the gun-mounting to gear with a 50 projection or recess on or in a non-recoiling part may obviously be reversed—that is to say, the pawl may be on the non-recoiling part and the projection or recess on or in the recoiling part. 55 Although in the drawings I have illustrated the auxiliary gearing adapted to be worked manually, I wish it to be understood that, if desired, such gearing may be worked by steam, electrical, or other power.

50 What I claim is—

1. In apparatus for working heavy guns, the combination of means for enabling the recoiling part of the mounting to be run out by auxiliary gearing in the event of the power 55 by which the gun is ordinarily run out to its firing position becoming inoperative, and of trip-gear adapted to maintain the gun in its

run-out position at any angle of elevation and to release the same and permit it to recoil on shock of discharge.

70

2. In apparatus for working heavy guns, the combination of means for enabling the recoiling part of the mounting to be run out by auxiliary gearing in the event of the power by which the gun is ordinarily run out to its 75 firing position becoming inoperative, and of trip-gear carried by a recoiling part of the mounting and adapted to engage with a non-recoiling part of the said mounting for the purposes specified.

80

3. In apparatus for working heavy guns, the combination of means for enabling the recoiling part of the mounting to be run out by auxiliary gearing in the event of the power by which the gun is ordinarily run out to its 85 firing position becoming inoperative, and of trip-gear, in the form of a spring-pawl, carried by the recoiling part of the mounting and adapted to engage with projections or recesses of a non-recoiling part of the mounting for 90 the purposes specified.

4. In apparatus for working heavy guns, the combination of means for enabling the recoiling part of the mounting to be run out by auxiliary gearing in the event of the power 95 by which the gun is ordinarily run out to its firing position becoming inoperative, of a spring-pawl carried by the recoiling part of the mounting, and of a sprocket-chain forming part of the auxiliary gearing and having 100 projections or recesses for engagement with the said pawl substantially as and for the purposes described.

5. In apparatus for working heavy guns, the combination with the auxiliary gearing, 105 the spring-pawl and the endless sprocket-chain forming part of the auxiliary gearing, of projections on said chain to engage with the said pawl, the distance apart of the said projections being such that when the gun is 110 in either its run-out position or its run-in position the said pawl will engage with one of the said projections substantially as and for the purposes specified.

6. In apparatus for working heavy guns, 115 the combination with the auxiliary gearing, and the spring-pawl, of projections on the non-recoiling part of the mounting such projections having inclined faces and of an inclined nose on said pawl to engage with said 120 inclined faces substantially as and for the purpose specified.

7. In apparatus for working heavy guns the combination with the auxiliary gearing, 125 the spring-pawl and the endless sprocket-chain having projections to engage with the pawl and forming part of the said auxiliary gearing, of a bracket on the recoiling part of the mounting through which bracket the said chain passes and by which it is supported 130 against the pressure of the spring-pawl substantially as and for the purpose specified.

8. The combination with the trip-gear, of auxiliary gearing comprising a toothed pin-

ion which is carried by an axle on a part of the mounting which moves about the axis of the gun-trunnions in elevating the gun and which pinion imparts forward movement to the recoiling part of the mounting, a wheel adapted to operate the auxiliary gearing and mounted on an axle which is carried by a part of the mounting that does not participate in the movements of the gun in its elevation, of intermediate gearing for operatively connecting together the said toothed pinion and the axle of the aforesaid wheel, and of a sliding shaft carrying said intermediate gearing, which shaft permits the relative position of the aforesaid two axles to change in accordance with the variation in the angle of elevation of the gun substantially as and for the purpose specified.

9. In apparatus for working heavy guns the combination with the means for enabling

the recoiling part of the mounting to be run out by auxiliary gearing in the event of the power by which the gun is ordinarily run out to its firing position becoming inoperative, of a pair of spring-pawls adapted to maintain the gun in its run-out position at any angle of elevation and to release the same and permit it to recoil on shock of discharge, and of a transverse lever pivoted to the recoiling part and adjustably supporting the springs of the said pawls as and for the purpose specified. 25 30

In testimony whereof I have hereunto set my hand, in presence of two subscribing witnesses, this 9th day of August, 1899.

ROBERT MATTHEWS.
